US00D614144S

(12) **United States Design Patent**
Arosio

(10) **Patent No.:** **US D614,144 S**
(45) **Date of Patent:** **** Apr. 20, 2010**

(54) **ACTUATOR**

(75) Inventor: **Oliviero Arosio**, Lissone (IT)

(73) Assignee: **GI.BIDI. S.R.L.**, Poggio Husco (IT)

(**) Term: **14 Years**

(21) Appl. No.: **29/309,290**

(22) Filed: **Jul. 21, 2008**

(30) **Foreign Application Priority Data**

Feb. 5, 2008 (EM) 000872734

(51) **LOC (9) Cl.** **13-03**

(52) **U.S. Cl.** **D13/166; D13/158**

(58) **Field of Classification Search** D13/158,
D13/166, 170, 174, 183, 184, 199; 439/717,
439/721, 725; D15/143, 199, 5, 7; 474/148;
74/89
